UNITED STATES PATENT OFFICE

2,380,528

RAILWAY CAR

Otto Jabelmann, Omaha, Nebr.; Teresa R. Jabelmann Administratrix of said Otto Jabelmann, deceased

Original application December 20, 1940, Serial No. 370,917. Divided and this application August 3, 1942, Serial No. 453,308

1 Claim. (Cl. 105—2)

This invention relates to vehicle bottom construction involving the use of a housing extending longitudinally of the vehicle between its sides for enclosing underneath equipment with aprons for controlling air currents at opposite sides of the housing, and the primary object of the invention is so to correlate the underneath equipment housing, the apron arrangement at the car sides, the plates underlying the underframe between the aprons and respective housing sides and between the truck pockets, and the folding step arranged at the ends of the car, that when the car is in motion and the steps are folded up against the trap doors the sheets carried by and concealing the underside of the step are substantially in line with the car body housing when in closed position so that effective streamlining of the bottom of the car may be achieved to reduce train resistance at high speeds to a minimum.

The invention contemplates a streamlined undersurface arrangement for a railway car wherein the space from a truck pocket on one car to the truck pocket on the adjoining car is smooth and streamlined with a step assembly so designed as to provide a surface flush with this smooth, flat under surface of the car body and within the projected plane of the equipment housing extending the length of the vehicle between trucks whereby the whole combination provides an arrangement avoiding the formation or raising of dust clouds from the road ballast as the car travels thereover at high speed.

The foregoing and other objects and advantages of the invention will be apparent from the following description taken in conjunction with the accompanying drawings, in which—

Fig. 1 is a side elevational view of a railway passenger-train car equipped in accordance with the invention and showing the streamlined vestibule arrangement, the apron depending from the car sides and the equipment housing extending between the trucks of the car;

Fig. 2 is a cross-sectional view taken on the line 2—2 of Fig. 1 through the lower portion of the car showing the apron arrangement associated with respectively adjacent housing sides for relieving side wind pressure against the housing sides by diverting the air outwardly and downwardly;

Figure 3 is a vertical, sectional view transversely of the car through the folding step and trap door at the ends of the car, taken on the line 3—3 of Fig. 1 and showing in full lines the position of the steps when folded up against the trap door between the body end sill and buffer

wings looking towards the adjacent truck, the step bottom cover plate being substantially within the projected zone of the body streamlining plates and the housing and the position of the steps when lowered being indicated in broken lines; and

Figure 4 is an enlarged fragmentary elevational view of the steps and adjacent buffer wing and body end sill members and trap door with the steps in raised position and showing the substantially streamlined relation of the step bottom cover plate and said members and body streamlining plate, the view being taken on line 4—4 of Fig. 3, looking in the direction indicated by the arrows.

This application is a division of my copending application, Serial No. 370,917, filed December 20, 1940, for Railway car, now Patent No. 2,318,863.

In the drawings, 10 represents the body of the car as a whole, 11 the underframe to which may be secured underneath equipment such as the water tanks 12 and fuel or air reservoirs 13 and other items of equipment arranged upon opposite sides of the longitudinal center of the car to prevent excessive swaying of the car body during train movement. In high-speed train movement for which this invention is particularly designed, it is important that all of the car body exposed to the action of winds tending to impede car travel be formed to present surfaces streamlined and free from projections which would offer possible obstruction to air flow with resultant lag in car movement. For cars fitted with underneath equipment, the desired streamlining of the underside of the car body is effected by means of a housing 15 for enclosing the motor, batteries, compressor and condenser units and control valves of the air conditioning system and formed to present smooth exterior surfaces at its opposite and lower sides, as best shown in Figures 1 and 2. The sides 16 of the housing are arranged to slope downwardly and inwardly to the connecting floor 17 of the housing and are secured at their upper margins 18 to respectively contiguous margins of laterally arranged extension plates 19 which extend longitudinally the full length of the car.

Upwardly and outwardly of the upper margins 18 of the housing sides 16 extend the laterally arranged plates 19 virtually the full length of the car and underlying the side sills 35 and cross members 20 of the underframe 11 to provide a smooth surface for the underside of the car body upon opposite sides of the housing proper to the

car sides, as best shown in Figure 2. Plates 19, extending longitudinally of the car, are joined at their outer edges to the car side sills 35 and supported at their inner margins by flanged members 18—a extending longitudinally between cross members 20 of underframe 11. That portion of the space 14 between the underframe members 20 of the underframe and between the underlying housing extension plates 19 and the floor 9 of the car and between the center sill 21 of the underframe and respectively adjacent car sides 8, constitutes, for all practical purposes, extensions of the enclosure capacity of the housing 15 to afford additional housing for the accommodation of drainage and water supply pipes and electrical supply cables and conduits customarily installed below the floor line and which likewise may be reached through access doors 6 in the housing sides 16 for the air conditioning system units before mentioned.

Depending from the sides 8 of the car upon opposite sides of the housing 15 and in operative relation to respectively adjacent housing sides 16 and lateral surfaces of plates 19 are the apron members for controlling and directing air currents developing under thrust of cross winds against the car and housing sides. The air directing and controlling aprons take the form of fixed and removable apron sections 22 and 23 respectively arranged lengthwise of the car and extending for at least the length of the housing 15, as indicated in Figure 1. The aprons include louvers 25 arranged in series and mounted to preserve the streamline contour of the body at respectively adjacent car sides 8, as best shown in Figure 2. The louvers may be of any approved type, but, as shown, are formed with their respective web portions bent or curved in cross-section, substantially as shown in Figure 2 to rigidify the louvers between their ends and stiffen them against possible distortion resulting from impacts against the apron sides. The louvers of the movable sections 23 of the apron members, are connected at their ends to supporting brackets 30 and are disposed with their outer margins in planes below their respective inner margins so that they may assume generally inclined positions with their bodies sloping downwardly and outwardly to provide air passages 29 having substantially the contour of the louvers.

The hanger brackets 38 supporting the movable apron sections 23 are pivotally hung from the car body, as at 32 and 33, whereby they may be removed to expose adjacent housing doors 3 to obtain access to the housing for inspection or maintenance of equipment parts underneath the car underframe. The relatively fixed brackets 34 support and brace the fixed portions 22 of the aprons, the louvers 25 of which are secured at their ends substantially in the same manner as that employed in mounting the louvers of the movable sections 23. The brackets are rigidly secured to side sills 35 and contiguous underframe portions 11. To prevent unauthorized removal or raising of the apron doors, suitable locking means are provided in the form of swivel bolts and wing nuts 68 to facilitate manipulation of the lock. The bearing pins 39 for the swivel bolts are preferably parallel with the pivotal axis of the movable door sections 23 so that they may be disconnected from, or brought into engagement with respectively adjacent fixed brackets 34 which are provided with keeper portions adapted to receive the swivel bolts with the nuts 68 in position to be tightened thereagainst. Both the fixed and mov-

able door portions of the aprons may be assembled in units of convenient length, end to end, to establish the continuity of the aprons further to enhance the streamline definition of the body lines. The aprons may be made up in greater part of fixed sections 22 and relatively few movable parts 23, as indicated in Figure 1, or they may comprise doors in excess of the number required in the present embodiment of the design, depending upon the type of the car and the number and position of the access doors 6 in the housing sides which vary with different types of cars—the length of the several sections being determined by the size and location of the various pieces of underneath equipment.

In operation, the air currents generated by the impact of cross winds against the car sides 8 would be deflected upwardly from the ground by the adjacent housing sides 16 and directed laterally toward the car sides by the plates 19 at the underframe, thence downwardly and outwardly by the louvers 25 of respectively adjacent aprons 22 and 23 whereby the resultant curtain of air discharged from the louvered aprons and surging downwardly away from the windows 3 and respective car sides functions to prevent abrasion of window glass and car body by entraining the ballast particles lifted by the air currents to carry them away from the car, all as indicated by the arrows in Fig. 2 showing the course of such air stream.

The streamlining effect underneath the car at the vestibule area is further enhanced by arranging the steps 30, when raised, to occupy a position in the space between transverse members 31 and 32 of the underframe 11 and enclosing the steps and, incidentally, the space by means of a cover plate 33 secured to the underside of the steps substantially within the projected lines of the bottom streamlining plates 19 and the housing 15 between the trucks, as best shown in Figs. 3 and 4 of the drawings.

The step construction comprises an upper fixed step cooperating with a movable step assembly which is pivotally mounted on trunnions 90 and formed with the usual risers 91 and treads 92 secured at their ends to hanger plates 93 to which the step-supporting trunnions 90 are attached and to which, at a point above the trunnions, one end of a bar 95 is secured connecting the steps to a trap door 96 hinged to the car by hinges 99 upon an axis at right angles to the pivotal axis of the steps. When the trap door is raised the steps are automatically lowered by the bar 95 as shown in Fig. 3 and when trap door is lowered the steps are automatically raised. The trap door is provided with suitable latching mechanism 98 whereby the trap door is properly held closed during train movement and with a suitable latching device for holding trap door in open position when the steps of the movable assembly are in lowered position. For the purpose of streamlining the portion of the car at the ends, the steps of the movable assembly are covered by an underlying plate 93 secured at its upper end to adjacent step riser 91' and at its lower end to flange on plate 96, which cooperates with plate 93 to provide a back streamlining housing for all the treads and risers of the movable step assembly except the top riser 91' thereof. Plate 93 is secured at its upper margin to contiguous outer flange 99 depending from adjacent step tread 92'. As best shown in Fig. 4, the streamlining plate underlying the steps may be secured adjacent its side margins to contiguous step hanger plates

93 the lower portions of which are adapted for connection with adjacent margins of the cover plate. It will be noted from an inspection of Fig. 3 that the cover plate 83 throughout its length shields the relatively large expanse of wind-brake surface presented by the step riser, hanger and step well faces to provide for the ends of the car a projected extension of the streamlined understructure defined by the housing 15 and under-frame cover surfaces 19 for that portion of the car between the trucks, to the end that excessive disturbance of roadbed and ballast resulting from quartering and side winds during train movement will be prevented. As indicated in Fig. 1, the smooth exterior characterising the streamlined definition of the body at the vestibules of the car is preserved at the step position by arranging the portion 98 of the back streamlining housing of the movable step assembly to be flush with the car side 8 or with a door in substantially the plane of the car side when steps are raised, as best shown in Fig. 3. The steps 80 and that portion of the area of the cover plate 83 for a substantial distance inwardly from the car side are disposed as near as may be within the projected contours of streamlining plates 19 and the housing 15 in order to reduce turbulence of air currents beneath the car to a minimum.

In the foregoing embodiment of the invention,

there has been provided a vehicle body having its underside effectively streamlined and substantially devoid of projecting surfaces, whereby the air currents induced by car movement or passing trains would be free to move unhampered for substantially the full length of the car.

What I claim is:

In a vehicle having an underframe and a body including a side wall, a bottom streamlining plate enclosing the undersurfaces of the underframe, and a vestibule step construction comprising the combination of a fixed step mounted between the body and said plate and a movable step assembly having a riser extending upwardly from its top tread and a back streamlining housing for the remainder of its treads and risers, said assembly being pivotally mounted for swinging movement beneath the fixed step between a lower operative position in which said riser substantially engages 15 said fixed step and an upper folded position in which said riser substantially engages the bottom streamlining plate and the back streamlining housing extends continuously from said riser to the side wall of the body, whereby said riser and 20 housing enclose the folded step assembly substantially within the upper and lower limits of the underframe and between the bottom streamlining plate and the body side wall.

OTTO JABELMANN.
